WILLIAM F. CONRAN, OF BROOKLYN, NEW YORK.

FLUSHING APPARATUS FOR WATER-CLOSETS.

1,288,387.

Specification of Letters Patent. Patented Dec. 17, 1918.

Application filed April 22, 1916. Serial No. 92,848.

To all whom it may concern:

Be it known that I, WILLIAM F. CONRAN, a citizen of the United States of America, residing in the borough of Brooklyn, city of New York, in the county of Kings and State of New York, have invented a certain new and useful Improvement in Flushing Apparatus for Water-Closets, of which the following is a specification.

10 The object of my invention is to provide a flushing apparatus in which the tank and exposed portions of the piping and valves normally contain no water. In flushing apparatus of this character it is desirable to 15 place the inlet or supply valve in a covered position to protect it from the cold. A second object of my invention is to arrange the supply valve and the flushing valve so that they will operate simultaneously, and further to arrange the valves and pipe connections so as to permit of quick inspection and 20 repair of the valves without disturbing or removing the supply and flushing valve casings or the piping connecting them with the 25 hopper and flushing tank. In carrying this latter object into effect I provide a pipe which serves both as a jacket for the water pipe which connects the two valves and as a means of permitting removal and replacement 30 of the moving parts without interference.

In the accompanying drawings Figure 1 is a view of the complete flushing apparatus embodying my invention. Fig. 2 is a central vertical section of the inlet or supply valve casing. Fig. 3 a central vertical section of the flushing valve and casing. Fig. 4 a central longitudinal section of the flushing valve. Fig. 5 a similar view of a modified form of flushing valve, and Fig. 6 is a plan view of the flushing valve showing relative position of the valve operating cams.

Referring to Fig. 1 of the drawings, 1 is 45 a hopper having a seat 2 secured to a seat-iron having a forked cam lever 3 pivoted at 4 to a post projecting from the flushing valve casing 5. The flushing valve casing has three threaded openings, one being connected by piping 6 with water tank 7; the second by pipe jacket 8 with the supply valve casing 9, and the third for the connection to the hopper. The supply valve casing has three openings; one to which pipe 8 is 50 threaded, the second being for the water service connection 10, and the third being

for the drain connection 11 leading to the usual waste pipe or trap 12.

The supply valve casing shown in vertical section in Fig. 2, is in the form of an elongated tubular casing 9 having its lower end reduced in diameter and externally screw-threaded as shown at 13 to receive the coupling of the water supply pipe 10; its upper end is enlarged and internally screw-threaded to receive pipe-jacket 8, and at a point about midway of the casing is the drain port 14 formed in a screw-threaded extension 15 to which is connected the drain pipe 11 as shown in Fig. 1. Within the casing 9 is formed the drain passage 16 leading from the upper end of the casing to the drain-port. The bore of the casing 9 is cylindrical, the lower end being of smaller diameter and terminating in the screw-threaded inlet end 13. Immediately above the inlet the inside diameter is increased to form a valve chamber 17 and valve seat 18.

The inlet or supply valve and the valve for controlling the drain port are formed in a single hollow cylindrical piece 19 having a circumferential groove 20 and port holes 21 in line with the drain port 14, and inlet holes 22 immediately above the closed lower end of the tube. At this part of the piece 19 the diameter is reduced to form a shoulder against which is placed a washer 23 of leather or other suitable material to form the inlet valve and which sets upon the seat 18. The end of piece 19 terminates in a feathered guide 24 which works in the inlet 13. The valve piece 19 has a smooth uniform outside diameter except at groove 20 and makes a close sliding fit in the reduced bore of the casing 9 and is carried by the pipe 25.

The flushing valve casing shown in vertical section in Fig. 3 has a central vertical bore within which is fitted a bushing 26, having an internal flange 27 at the center to form a seat for the flushing valve, and two ports 28 and 29 leading, respectively, to the hopper and tank. Ports 28 and 29 are maintained in proper position by seating the bushing on a shoulder 8^a and by a pin 30 which holds the bushing against rotation. The top of the flushing valve casing is closed by a plate cap 31 secured by screws to the flange 32 with a layer of suitable packing material 33 between the plate and the flange. 110 Plate 31 has a central screw-threaded packing chamber through which the valve stem

passes, and receives the screw-threaded packing sleeve 34 on the valve stem. The post on which the hopper seat is pivoted is shown at 35.

5 The flushing valve comprises a hollow stem 36, externally screw-threaded at both ends; a flanged internally threaded coupling 37, a valve washer 38 of any suitable material, and which makes a close fit within 10 bushing 26; a metal washer 39 and a nut 40. The lower end of coupling 37 receives the upper end of pipe 25. Above the nut 40 the valve stem is perforated as shown at 41 and between the nut and the packing chamber 15 the stem carries a spiral spring 42 whose function is to move the valve stem downward. The upper or exposed end of the valve stem 36 receives a lifting head 43, which may be of any desired form to engage 20 with the forked cam 3 of the hopper seat.

It will now be noted that the inlet valve and flushing valve are mechanically connected together by pipe 25 and that the flow of water is from the inlet 13 to the inlet 25 valve chamber 17; from chamber 17 through openings 22 to the interior of inlet valve 19; through pipe 25 to valve stem 36 and through the openings 41. In other words, the inlet and flushing valves are connected 30 by or mounted on a common valve stem which is hollow and constitutes the water-way between the two valves.

In Fig. 5 is shown a modification of the flushing valve of Figs. 3 and 4, similar parts 35 being indicated by the same reference numerals. In this form, instead of screwing stem 36 directly into the coupling member 37, the stem is provided with a head 44, and a male coupling member 45 is substituted 40 for nut 40, and this coupling member screws into coupling 37; the washers 38 and 39 being clamped between the flanges of the coupling members. In this form stem 36 is 45 flexibly connected with the valve to overcome binding of movable parts in case the two valve casings are not in proper alignment.

In setting up the flushing apparatus, the two valve casings are placed in their respective 50 positions with the connecting pipe jacket 8 and other pipe connections completed, but without the valves, connecting pipes 25 and 36, bushing 26 and cap 31.

The inlet and flushing valves with their 55 hollow stems 25 and 36 are assembled before placing in position and when assembled are inserted through the flushing valve casing, the inlet valve passing through pipe jacket 8, and entering its casing; the position 60 of the flushing valve on the hollow stem having been previously determined so that the flange of the coupling member 37 will not strike shoulder 8^a and insure the seating of washer 23 of the inlet valve on seat 18. 65 Bushing 26, pin 30, spring 42, and cap 31,

are then placed in position; then the packing material is inserted and sleeve 34 screwed down. The seat is then hinged to post 35 and lifting head 43 is screwed on stem 36 and adjusted so that the downward movement of the hopper seat will raise the valve stems and valves until the flushing valve seats against flange 27. To withdraw the valves and co-operating parts from the casings all that is necessary is to remove the 75 screws which secure cap-plate 31, and then by taking hold of lifting head 43, the valves, stems, spring, bushing and cap-plate are withdrawn; the parts including the cap-plate passing between the forks of cam lever 3.

The operation of the flushing apparatus will be readily understood from the foregoing description of the parts, and may be briefly stated as follows: In the position of 85 the parts as shown in the drawings, which is the normal position, the inlet valve is closed shutting off the water supply and the flushing valve is open. When in use, seat 2 is depressed and cam lever 3 acting on lifting head 43 moves valve stems 36 and 25, seating the flushing valve against flange 27, unseating the inlet valve, and moving groove 20 and perforations 21 above drain port 14 which is now closed by the inlet valve body. 95 Through the upward movement of the valve members, spring 42 is compressed. Water now enters chamber 17 and perforations 22 and passes through hollow valve stem 25 and the flushing valve, and out through the perforations 41, and through the pipe 6 to the tank. When the pressure on the hopper seat is removed, spring 42 will move the valve members downward to the normal position 100 shown in the drawings, shutting off the water supply, and opening the flushing valve and drain port. The water now flows from the tank through the ports of bushing 26 and into the hopper with practically a direct flow. After the tank is empty the water remaining in the valve stem 25 above the line of the drain port, and whatever water 105 may leak around the flushing valve into the jacket 8 will now drain off through perforations 21, passage 16, and drain pipe 11. 110

115 What I claim is:

1. In a flushing apparatus for water closets, the combination with a hopper and a flushing tank, of a flushing valve casing having two ports opening into pipe connections projecting at right angles to the casing, one connected to the hopper and the other opening on a higher level and connected to the tank, a valve seat between the ports, a flushing valve for controlling communication between said ports, an independent supply valve casing for connection to the water service, supply and drain valves in said casing, a pipe-jacket rigidly connecting the two valve casings, a movable 120

125

130

water conveying pipe within the jacket and connecting said flushing and supply valves and having its outlet above the flushing valve, an operating stem projecting vertically from the flushing valve through the cap of the flushing valve casing for moving said water conveying pipe to operate said valves simultaneously, and said casings and valves being constructed to permit insertion or removal of said valves and the opening or closing of the casing without rotary movement of any of the valve parts.

2. In a flushing apparatus for water closets, the combination with a hopper and a flushing tank, of a flushing valve casing having two ports opening into pipe connections projecting at right angles to the casing, one connected to the hopper and the other opening on a higher level and connected to the tank, a removable bushing within said casing having openings registering with said ports and a valve seat between said openings, a flushing valve for controlling communication between said ports, an independent supply valve casing for connection to the water service, supply and drain valves in said casing, a pipe-jacket rigidly connecting the two valve casings, a movable water conveying pipe within the jacket and connecting said flushing and supply valves and having its outlet above the flushing valve, an operating stem projecting vertically from the flushing valve through the cap of the flushing valve casing for moving said water conveying pipe to operate said valve simultaneously, and said casings and valves being constructed to permit insertion or removal of said valves and bushing, and the opening or closing of the casing without rotary movement of any of the valve parts.

3. In a flushing apparatus for water closets, the combination with a hopper and a flushing tank, of a flushing valve casing having a cylindrical bore and two ports opening into pipe connections projecting at right angles to the casing, one connected to the hopper and the other opening on a higher level and connected to the tank, a removable bushing within said bore having openings registering with said ports and a flange between said openings forming a valve seat, means for maintaining said openings in alinement with said ports, a flushing valve for controlling communication between said ports, an independent supply valve casing for connection to the

water service, supply and drain valves in said casing, a pipe-jacket rigidly connecting the two valve casings, a movable water conveying pipe within the jacket and connecting said flushing and supply valves and having its outlet above the flushing valve, an operating stem projecting vertically from the flushing valve through the cap of the flushing valve casing for moving said water conveying pipe to operate said valves simultaneously, and said casings and valves being constructed to permit insertion or removal of said valves and bushing, and the opening or closing of the casing without rotary movement of any of the valve parts.

4. In a flushing apparatus for water closets, the combination with a hopper and a flushing tank, of a flushing valve casing having a cylindrical bore and two ports opening into pipe connections projecting at right angles to the casing, one connected to the hopper and the other opening on a higher level and connected to the tank, a removable bushing within said bore having openings registering with said ports and a flange between said openings forming a valve seat, means for maintaining said openings in alinement with said ports, a flushing valve within said bushing and arranged to seat against the underside of said flange to close the passage between said ports and when unseated to close the lower end of said bushing below the hopper port, an independent supply valve casing for connection to the water service, supply and drain valves in said casing, a pipe-jacket rigidly connecting the two valve casings, a movable water conveying pipe within the jacket and connecting said flushing and supply valves and having its outlet above the flushing valve, an operating stem projecting vertically from the flushing valve through the cap of the flushing valve casing for moving said water conveying pipe to operate said valves simultaneously, and said casings and valves being constructed to permit insertion or removal of said valves and bushing, and the opening or closing of the casing without rotary movement of any of the valve parts.

This specification signed and witnessed this eleventh day of April, 1916.

WM. F. CONRAN.
